REFRIGERATING APPARATUS

William W. Watt, Dayton, Ohio, assignor to General Motors Corporation, Dayton, Ohio, a corporation of Delaware

Application March 5, 1936, Serial No. 67,409

1 Claim. (Cl. 230—221)

This invention relates to compressors of refrigerating systems and particularly to check valves ordinarily incorporated in the piston or pistons of such compressors.

5 In refrigerating systems embodying a compressor which divides the system into a high pressure portion or side and a low pressure portion or side and which compressor includes a single piston valve, for permitting flow of refrigerant from the compressor crankcase or from the low pressure portion of the refrigerating system into the compressor cylinder to permit compression thereof by the piston, it has been found that an abnormal low pressure is created in the compressor cylinder above the piston upon the initial 10 downward movement of the piston and prior to the opening of the piston valve. The abnormal low pressure in the cylinder causes refrigerant vapor, from the compressor crankcase or from the low pressure portion of the refrigerating system, to suddenly rush into the cylinder above the piston when the piston valve opens with such force that a loud popping noise is created. This noise occurs at each and every downstroke of the piston or pistons during operation of a compressor and is very objectionable. Many different 15 valve constructions have been made in an endeavor to overcome this objectionable noise and to provide a quiet operating compressor. For example, numerous types of single valves have been tried without satisfactory results. Applicant's invention is therefore directed to the provision of a double valve arrangement or to two valves in series relation within a compressor 20 piston which successfully eliminates the objectionable noise referred to.

An object of the present invention is to provide an improved compressor for a refrigerating system.

40 Another object of the present invention is to provide a valve structure or arrangement within the piston of a compressor which will operate efficiently and quietly in order that the compressor in which the valve arrangement is incorporated may be used in refrigerating apparatus of the household type.

A further object of the present invention is to provide a valve construction or arrangement within the piston of a compressor of a refrigerating system which will be of long life and quiet in operation.

In carrying out the foregoing objects it is a still further and more specific object of the invention to provide two valves one in series with the other in a piston of a compressor of a refriger-

ating system in order to eliminate noise inherently present in the operation of compressors having but a single valve within a piston thereof.

Further objects and advantages of the present invention will be apparent from the foregoing description reference being had to the accompanying drawings, wherein a preferred form of the present invention is clearly shown.

In the drawings:

Fig. 1 is a sectional view of a compressor of a refrigerating system having the present invention embodied therein and showing the refrigerating system diagrammatically connected to the compressor;

Fig. 2 is an enlarged vertical sectional view of the piston of the compressor shown in Fig. 1 having my improved valve arrangement incorporated therein;

Fig. 3 is a view taken on the line 3—3 of Fig. 2 showing the valve arrangement incorporated in the compressor piston partly in section and partly in elevation; and

Fig. 4 is a sectional view through the piston taken on line 4—4 of Fig. 2 and showing in plan one of the valves of the valve arrangement incorporated in the piston.

Referring to the drawings for illustrating the present invention, I have shown a refrigerating system of the type suitable for installation in small refrigerators of the household variety. This type of apparatus is usually installed in cabinets which are placed in localities where noise caused thereby will be objectionable. Apparatus of this type must be automatic in operation and such operation thereof must be carried out quietly. The apparatus or system may comprise a compressor, generally represented by a reference character 10, discharging refrigerant under pressure through a conduit 11 to a condenser 12.

The compressed refrigerant is cooled and liquefied in condenser 12 in any suitable or conventional manner and flows into a chamber 13 containing a float or otherwise operated valve which controls the flow of liquid refrigerant to the evaporator 14. Refrigerant vaporized in evaporator 14 is drawn through a conduit 15, by suction created by the compressor 10, back to the compressor preferably to the crankcase thereof. The evaporator 14 is adapted to be mounted within an insulated compartment of refrigerator cabinet (not shown) from which heat is to be extracted. Means for controlling a motor 16 which operates the compressor 10, through suitable belt and pulley connections 17, in response to the temperature produced by the evaporator 14

may be provided. This means may comprise an expandible bellows 18 connected by a pipe 19 to a bulb 21, mounted in thermal association with the evaporator 14, and having a volatile fluid sealed therein for actuating, upon movement of the bellows 18, a switch 22 interposed in the power line leading to motor 16.

Operation of motor 16 drives the compressor shaft 23 through the connections 17. Rotation of compressor shaft 23 causes rotation of eccentrics 24 and 25 mounted thereon for operating the pitmen 26 and 27 respectively to cause the compressor pistons 28 to be reciprocated within the cylinders 29. The end of the shaft 23 which extends through a wall of the compressor crankcase may be sealed by any suitable or conventional sealing means generally indicated at 31. Outlet check valves, 32 of the type fully disclosed in the Patent No. 1,852,203 to Otto M. Summers on April 5, 1932, mounted within the compressor 10 upon a suitable plate located above the cylinders 29 together with the refrigerant flow control means 13 divide the refrigerating system into a low pressure portion and a high pressure portion. The low pressure portion of the refrigerating system includes the evaporator 14, conduit 15 and the crankcase of compressor 10. The valve arrangement in the present disclosure employed to intermittently open and close the passage extending through the pistons 28 and which passages establish communication between the crankcase of compressor 10 and the cylinders 29, comprise the valves 35 and 36 mounted within the pistons 28 one above the other in series relation with the path of flow of refrigerant through the pistons. Referring now to Fig. 2 it will be noted that the lower valve 35 is in the form of a disk which seats upon the seat 31 surrounding an opening provided in a horizontal part 38 of a cylindrical spider like member 39 mounted and secured to the piston 28. The spider like portion 41 of member 39 includes a downwardly projecting central stem 42 having a shoulder formed thereon which receives an open walled cage member 43. The cage member 43 encloses and holds in place the disk valve 35 and spring 44 (see Fig. 4) which is adapted to bear against valve 35 to normally maintain this valve upon the seat 31, the horizontal part 38 of member 39 may be welded or staked to member 39 after the cage 43, spring 44 and valve 35 have been mounted or located within the cylindrical cup like portion of the member 39 and prior to assembly of the member 39 into the piston 28. The cylindrical spider like member 39 is provided with a valve seat 46 upon its upper face and after the member 39 is placed in the hollowed out receiving portion therefor provided in the piston 28 the upper piston valve 36 is adapted to be located upon this seat 46. A plate 47 having perforations therein providing guiding edges 48 (see Fig. 3) for valve 36 is placed upon the member 39. The plate 47 has a relatively thin plate 51, perforated as at 52, welded, staked or otherwise secured thereto prior to assembly of plate 47 upon the piston 28. The thin perforated plate 51 has a spring 53 secured to its under surface in any suitable or desirable manner. Spring 53 may have its one end 54 (see Fig. 3) located in a slot (not shown) provided or cut in plate 47 and is adapted to normally hold valve 36 against its seat 46. Both plates 47 and 51 and the outwardly flanged part of member 39 are provided with openings which receive screws 55 adapted to be threaded into threaded openings 56 provided in the piston 28.

The heads of screws 55 tightly clamp the plates 47 and 51 and the cylindrical spider like member 39 in position in or on the piston. It will be seen that the passage through piston 28 is normally closed by two valves arranged one above the other and in series relation with the flow of fluid through the passage.

When the pistons 28 are reciprocated, during operation of compressor 10 by motor 16, suction created by the initial downward movement of a piston in the cylinder 29 causes the upper valve 36 to be raised from its seat 46. This initial movement of piston 28 thereby establishes communication between the upper portion of cylinder 29 and the chamber provided by the member 39 within piston 28 to thus temporarily destroy or eliminate the enormous low pressure ordinarily created within the cylinder by a compressor piston having but a single valve incorporated therein. It is to be understood that during this initial movement of piston 28 and opening of valve 36 the lower valve 35 remains in closed position. Opening of the upper valve 36 while the lower valve remains closed in the manner described eliminates the objectionable popping noise which occurs or which is created in the manner hereinbefore pointed out. Further downward movement of piston 28 then increases the suction created above the piston and in the chamber of the piston below valve 36 to cause the lower piston valve 35 to open. Refrigerant gas or any other fluid may then freely pass through the valved passages provided in piston 28 into the compressor cylinder 29 above the piston. Both valves 35 and 36 will close at the bottom of the stroke of the piston 28 and the refrigerant vapor trapped in cylinder 29, between the top of piston 28 and the outlet check valve 32 will be compressed and forced under pressure, through the outlet opening at the top of the cylinder and controlled by valve 32, into the condenser 12 through conduit 11. The chamber provided in piston 28 by the member 39 is small and its volume does not therefore greatly reduce the volume of fluid flowing into the cylinder 29 and adapted to be compressed by the piston. The efficiency of the compressor 10 is thus not materially impaired by my improved double piston check valve arrangement.

From the foregoing it is apparent that I have provided an improved valve construction or arrangement for compressors which is quiet in operation and capable of operation over a long period of time. My improved double piston valve arrangement is constructed so as to be of maximum efficiency while at the same time eliminating objectionable noises inherent in the operation of ordinary compressors having but a single valve incorporated in the piston or pistons thereof. The improved piston and double valve construction can be manufactured and assembled in a compressor at low cost to render the compressor capable of use in systems such as refrigerating systems of household refrigerating apparatus where quiet operation of the compressor is of paramount importance.

While the form of embodiment of the invention as herein disclosed, constitutes a preferred form, it is to be understood that other forms might be adopted, all coming within the scope of the claim which follows.

What is claimed is as follows:

In combination with a piston adapted to be reciprocated within a cylinder of a compressor and having a passage therethrough for conveying

a fluid from one side of the piston into the cylinder on the opposite side thereof, a disc valve for controlling the passage of fluid through said piston, spring means for normally maintaining said valve in closed position, a second disc valve for also controlling the passage of fluid through said piston, said valves being carried by said piston in series relation one above the other, spring means separate from said first named 10 spring means for normally maintaining said second valve in closed position, said spring means for one of said valves being constructed and arranged to cause said one valve to move into

open position in response to suction pressure created on one side thereof by a predetermined initial movement of said piston within the cylinder, and said spring means for the other of said valves being constructed and arranged to cause said other valve to remain closed during movement of said one valve to open position and to cause movement of said other valve into open position in response to suction pressure created on the one side thereof after opening of said one valve upon movement of the piston beyond said predetermined initial movement thereof.

WILLIAM W. WATT.
